UNITED STATES PATENT OFFICE.

ADOLPH DIETSCHÉ, JR., OF NEW YORK, N. Y., ASSIGNOR TO AMERICAN LITHOGRAPHIC COMPANY, OF NEW YORK, N. Y., A CORPORATION OF NEW YORK.

DISPLAY DEVICE.

Application filed March 7, 1922. Serial No. 541,851.

To all whom it may concern:

Be it known that I, ADOLPH DIETSCHÉ, Junior, a citizen of the United States, and a resident of New York, borough of Queens, in the county of Queens and State of New York, have invented certain new and useful Improvements in Display Devices, of which the following is a specification.

This invention relates to display devices and has for its object to provide a display device in the form of a stand, adapted to securely support one or more containers, particularly common paper cartons, in such prominent manner as to attract attention.

Another object is to provide means, integral with the device, for positively engaging the container, preventing its inadvertent displacement, means also being provided to prevent the device from overturning. A

further object is to provide a unitary display device that can be cheaply constructed of inexpensive material, the exposed area being adapted to receive inscription, as advertisements of the goods in the containers.

These several objects are secured by the novel construction and disposition of parts formed preferably from a single blank in the manner hereinafter described and shown in the accompanying drawings relating thereto, and in which:

Figure 1 is a perspective front view of the preferred embodiment of the device and illustrates its application. Fig. 2 is a transverse sectional view taken on line 2—2 of

Fig. 1. Fig. 3 is a plan view of the unitary blank prior to being erected. Fig. 4 is a perspective front view showing a modified form of the display device as applied. Fig.

5 is a similar but rear view of the same.

Fig. 6 is a plan view of the blank from which said modification is erected. Figs. 1, 2, 4 and 5 are to one scale, while Figs. 3 and 6 are each to another and smaller scale.

The material of which the display device is constructed may be any flat sheet stock capable of being die cut to present a blank having a wall portion, 5, and base 6, their contiguous edges being articulated along bending line 7. The profile or contour of the

blank may be plain or as fanciful as desired, preferably symmetrical about its vertical median plane, for obvious reasons. As shown in Figs. 1, 2 and 3, the device is arranged to engage three cartons independ-

space at the left is vacant in order to clearly illustrate the structure.

Near each end of wall 5, at a height from the base corresponding to the height of the cartons, the material is incised to produce downreaching wings 8, and which may be substantially rectangular in contour, bounded by bottom edge 9 and side edges 10 terminating upwardly at points about coincident with the top of the carton, as 11. Said wings are adapted to be raised slightly from the general plane of wall 5 and inserted between the rear vertical wall of the carton and the intucked cover flap, said wing 8 being narrower than the carton so that the carton will cover the opening between cuts 10. Said carton may rest upon base 6, as best shown at the right hand end of Fig. 1, the arrangement being such as to hold the carton firmly against the wall and also prevent it from moving laterally on the base.

The center carton, 12, is shown held to the wall by down-reaching wing 14, formed from wall 5 by side cuts 15 and bottom cut 16, said wing having two transverse folding lines 17 and 18, at the top and near the bottom, respectively, presenting when bent, a tab 19. The width of wing 14 is such as to substantially cover the top of the carton and tab 19 is bent on said second folding line to be inserted between the front vertical body wall of the carton and its intucked cover flap, the function of said tab being similar to that of wings 8 in maintaining the cartons in position, and opening 14', caused by extending the wing horizontally, is obscured by the carton, as is apparent.

In some cases, in order to further support the device to maintain wall 5 in upright position, one or more easels may be formed to extend to the rear from said wall, preferably back of one of the cartons, the same being shown at the left hand end of Figs. 1 and 3. Said easel support, as 20, is formed by incising wall 5, as at 21, the cut extending from transverse cut 9 to bending crease 7, and preferably within the space covered by a carton. A vertical crease, 22, is formed in a similar manner from near the opposite end of cut 9 to crease 7, the same acting as a hinge by which the easel is articulated, and which permits said easel to be extended rearwardly at right angles to wall 5. Means of known character are provided to retain the easel when extended, the same consisting of

semi-circular detent 23, sheared from wall 5 centrally about bending line 22 at a point about midway its height and bent to extend outwardly on horizontal crease 24. The upper, curved edge of said detent has a recess 25 suited to receive an edge of the easel.

Although the modification illustrated in Figs. 4, 5 and 6 shows a narrower blank adapted to receive a single carton, the 10 width is optional and can be increased to suit requirements. The main upright portion, 30, of the blank has a single central longitudinal incision, 31, bisecting a transverse cut, 32, partially separating base 33, 15 articulated by crease lines 34, extending from the side edges inward to cut 32. The upper end of incision 31 bisects a cut line, 35, preferably curved upwardly to join straight longitudinal incisions 36, spaced 20 apart and in parallelism, to suit the width of the carton to be engaged by the device. Articulating crease 37 connects the upper ends of incisions 36, permitting the bending of wing 38 outwardly to rest over the 25 carton, tab 39 of wing 38 bending on line 40 to be entered between the front vertical wall of the carton and its intucked cover flap, as best shown in Fig. 4. At the same time easel members 41 are out-turned on 30 articulating creases 42, the same being in alignment with incised lines 36 and extending between the ends of incisions 35 and 32.

In erecting the device of this modification, the carton is pressed to extend partially 35 through the opening originally occupied by elements 38, 39 and 41, which, when tab 39 is adjusted, maintain the carton free from movement and at the same time the easel elements 41 are held extended by the carton 40 in opposite direction to that of base 33, providing an efficient support for the device. From the foregoing it will be seen that a unitary display device is disclosed, capable 45 of sustaining cartons in an erect position when its articulated parts are extended, and which, when in flat blank form, can be packed in small compass for shipment or storage, the matter of erecting being clearly apparent.

50 I claim:

1. In a display device formed unitary from a sheet of material the combination of a wall portion and a base portion, a fold-

ing line in said sheet connecting said portions, a downreaching wing formed from 55 said wall, the lower edge of said wing being spaced apart from said folding line, and an easel portion formed from said wall between said wing and folding line and articulated to said wall along a line approximately normal to said folding line, the width of said easel portion being less than the width of said wing.

2. In a display device of sheet material adapted to display a container comprising 65 vertical body walls and having a cover provided with a flap adapted for tucking in against the upper portion of one of said body walls, the combination of a wall and a base, a folding line therebetween, a downreaching wing formed from said wall, the lower edge of said wing being spaced apart 70 from said folding line, and an easel portion formed from said wall between said wing and folding line and articulated to said wall along a line approximately normal to 75 said folding line, the width of said easel portion being less than the width of said wing, said wing being adapted for insertion between the vertical body wall and the 80 intucked cover flap of the container.

3. In a display device of sheet material adapted to display a container comprising 85 vertical body walls in having a cover provided with a flap adapted for tucking in against the upper portion of one of said body walls, the combination of a wall and a base, a folding line therebetween, a downreaching wing formed from said wall, said 90 wing having two transverse folding lines 95 thereacross, the first at its jointure with said wall and the second spaced therefrom, and an easel portion formed from said wall between said wing and folding line and articulated to said wall along a line approximately normal to said folding line, the width of said easel portion being less than the width of said wing, said wing being adapted to overlie the top of a container, that portion of said wing beyond said second folding line being adapted for insertion 100 between the vertical body wall and the intucked cover flap of the container.

In witness whereof, I hereby affix my signature this 3rd day of March, 1922.

ADOLPH DIETSCHE, JR.
